MAGNETIC TAPE DECK

Earl J. Peterman, Mountain View, Calif., assignor to
Metrotech, Inc., Mountain View, Calif., a corporation
of California

Filed June 19, 1968, Ser. No. 12,435

Term of patent 14 years

Int. Cl. D14—01

U.S. Cl. D26—14

FIG. 1

FIG. 2

FIG.3

FIG.4

FIG. 1 is a perspective view of a magnetic tape deck showing my new design;

FIG. 2 is a top plan view thereof;

FIG. 3 is a front elevation thereof, the rear side of the tape deck base is plane; and

FIG. 4 is a side elevation as seen from the right of FIG. 1, the undisclosed left side is a mirror image of the right side.

The dominant feature of my design resides in the portions shown in full lines.

I claim:

The ornamental design for a magnetic tape deck, as shown and described.
